CLAIM

The ornamental design for a touch screen thermostat, as shown and described.

DESCRIPTION

FIG. 1 is a front and right side perspective view of the touch screen thermostat;

FIG. 2 is a front elevation view of the thermostat of FIG. 1; FIG. 3 is a right elevation view of the thermostat of FIG. 1; FIG. 4 is a bottom plan view of the thermostat of FIG. 1; FIG. 5 is a top plan view of the thermostat of FIG. 1; and, FIG. 6 is a left elevation of the thermostat of FIG. 1.

The rear elevation view of the thermostat of FIG. 1 is not shown because no claim is made to ornamentation on the rear of the thermostat.
